LOOSE LEAF BINDER

Robert R. Webb, Rosemead, Calif., assignor, by mesne assignments, to The Todd Company, Inc., a corporation of New York

Application September 3, 1954, Serial No. 32,161

Term of patent 14 years

(Cl. D6—2)

FIG. 1.

FIG. 3.

FIG. 2.

FIG. 4.

FIG. 5.

Fig. 1 is a top plan view of a loose leaf binder showing my new design, the side opposite thereto being substantially identical in appearance;

Fig. 2 is an end elevational view thereof;

Fig. 3 is a side elevational view;

Fig. 4 is a plan view of the inner surfaces thereof as it appears in separated position; and

Fig. 5 is an enlarged sectional view thereof taken on line 5—5 of Fig. 1.

I claim:

The ornamental design for a loose leaf binder, as shown and described.
